(57) **CLAIM**

The ornamental design for a can end, as shown and described.

DESCRIPTION

Fig. 5.1 is a top view of an embodiment of a can end showing our new design;

Fig. 5.2 is a bottom view thereof;

Fig. 5.3 is a side view thereof;

Fig. 5.4 is a side view thereof;

Fig. 5.5 is a top perspective view thereof;

Fig. 5.6 is a top perspective view thereof;

Fig. 5.7 is a side perspective view thereof;

Fig. 6.1 is a top view of another embodiment of a can end showing our new design;

Fig. 6.2 is a bottom view thereof;

Fig. 6.3 is a side view thereof;

Fig. 6.4 is a side view thereof;

Fig. 6.5 is a top perspective view thereof;

Fig. 6.6 is a top perspective view thereof;

Fig. 6.7 is a side perspective view thereof;

Fig. 7.1 is a top view of another embodiment of a can end showing our new design;

Fig. 7.2 is a bottom view thereof;

Fig. 7.3 is a side view thereof;

Fig. 7.4 is a side view thereof;

Fig. 7.5 is a top perspective view thereof;

Fig. 7.6 is a top perspective view thereof;

Fig. 7.7 is a side perspective view thereof.
